UNITED STATES PATENT OFFICE.

ERNST BREITLING, OF ESSEN, GERMANY, ASSIGNOR TO FRIED. KRUPP AKTIENGESELLSCHAFT, OF ESSEN-ON-THE-RUHR, GERMANY.

CASH REGISTER.

Application filed May 8, 1925, Serial No. 28,959, and in Germany June 16, 1924.

This invention relates to cash registers having differentially movable members influenced by keys and in which the depression of a key of a row of keys causes a determined 5 positioning of the corresponding differentially movable member. Devices of this character are made use of for instance when the keys of one row are designed to select transactions, while the keys of the other 10 row are sellers' keys.

According to the invention two of the differentially actuated members of two key rows arranged side by side are in connection with each other in such a manner that the 15 differential movement of the one member can be stopped through the medium of the other one.

With these and incidental objects in view, the invention consists in certain novel features of construction and combinations of parts, the essential elements of which are set forth in appended claims, and a preferred form of embodiment of which is hereinafter described with reference to the drawings 25 which accompany and form part of the specification.

In these drawings the subject-matter of the invention is illustrated as applied to a cash register having a plurality of totalizers 30 arranged in a drum.

In the drawings:

Fig. 1 is a front elevation of the cash register with the drum in a longitudinal section, some parts being omitted for the sake 35 of clearness,

Fig. 2 is a section on the line 2—2 of Fig. 1,

Fig. 3 is a cross-section of the drum on the line 3—3 of Fig. 1,

Fig. 4 is a section on the line 4—4 of Fig. 1,

Fig. 5 is a view corresponding to Fig. 4 with some parts in a different position,

Fig. 6 is a section on the line 6—6 of Fig. 1,

Fig. 7 is a view of the device for throwing the totalizers into and out of zero position,

Fig. 8 is the same device with the totalizer thrown in,

Fig. 9 is a fragmentary rear elevation of the drum,

Fig. 10 is a plan view of two differentially movable members, partly in section,

Fig. 11 is a front elevation of these members, partly in section. 55

Mounted on the casing partitions A are four rows of amount keys B, Figs. 1 and 2, and two rows of special keys C, Figs. 1 and 4, namely a row of sellers' keys I to V and a row of line of transaction keys A, C, R. 60 The amount keys B cooperate with feelers b³, Fig. 2, of coupling bolts b² pivoted to differential members B¹, the sellers' keys cooperate with a feeler c³, Figs. 10 and 11, of a coupling bolt c² pivoted to a differential member C¹ and the keys A, C, R cooperate with a feeler c³, Figs. 4, 5, 10 and 11, of a coupling bolt c² pivoted to a differential member C¹. 65

The differential members B¹, Fig. 2, which 70 are freely rotatable on a shaft B⁴, are actuated by means of driving members formed by engaging disks b⁵ rigid to the said shaft and to which a crank gear imparts an oscillating movement at each operation of the machine. 75 The crank gear comprises a crank b⁶, Figs. 1 and 6, fast to the shaft B⁴ and connected by a rocking rod d¹ with a crank d² carried by a short shaft D. The shaft D which is mounted in the casing A¹, is connected with 80 the driving shaft D⁵ by pinions d³, d⁴ and executes a revolution at each operation of the cash register. When the engaging disk b⁵ moves upwardly its shoulder b⁷ (Fig. 2) 85 engages the coupling bolt b² and carries the differential member B¹ along with it until, by the feeler b³ striking against the foot of the depressed key B, the coupling bolt b² is brought out of engagement with the shoulder b⁷ of the disk b⁵ and into engagement 90 with a series of teeth a² of the key bank whereby the differential member B¹ is locked. During the downward movement of the engaging disk b⁵ a pin b⁸ carried by the same 95 strikes against the differential member B¹ and returns it into zero-position.

The pinion d³ meshes with a pinion e¹ of the same size, Figs. 1 and 6, fixed to a shaft E which carries a disk E² provided with a cam groove e³, Figs. 4 and 5. As the pinion d³ executes a revolution at each operation of the machine as mentioned above, the disk E² has likewise imparted to it a revolution at each operation of the machine. The cam groove e³ is engaged by a roller c⁵ carried by a pitman C⁴. The pitman C⁴ is guided by 100 105

its fork-shaped end on the shaft E and pivoted by its other end to a rocking lever C⁷ which is mounted on a shaft c⁶. The free end of the lever C⁷ is in pivotal connection 5 with a link C⁸ pivotally connected by a pin c⁹ with one of the two engaging disks c¹⁰ for the differential members C¹ and C⁰ which are mounted for rotation on the shaft B⁴ like the disks c¹⁰. The two engaging disks 10 c¹⁰ are rigidly connected with each other through a sleeve c²² rotatable on the shaft B⁴, see particularly Fig. 10. The described mechanism will impart to the two engaging disks c¹⁰ an oscillatory movement at each 15 operation of the machine, the cam groove e⁸ being of such a shape that, during the downward movement of the disks b⁶ appropriate to the amount keys, there will take place the full oscillatory movement (downward and 20 upward) of the special key engaging disks c¹⁰, so that the last-said oscillatory movement will be terminated prior to the beginning of the adding movement of the amount differential members B¹ which takes place 25 during the upward swinging movement. During the upward swinging movement of the engaging disks c¹⁰ their shoulders c¹² engage the coupling bolts c² and carry along with them the two differential members C¹ 30 and C⁰ until their feelers c³ strike against the feet of the depressed special keys. During the downward movement of the disks c¹⁰ pins c¹³ carried by them strike against the differential members C¹ and C⁰ and return 35 the latter to zero position. If none of the special keys "A, C, R" is depressed, the appropriate feeler c³ is stopped and the respective differential member C¹ uncoupled and locked by other means. The pivot pins 40 c¹⁶, Figs. 4, 5, 11, of the feelers c³ of the differential members C¹ and C⁰ are provided with extensions (stop pins c¹⁷ and c²², Fig. 11) which pass through a slot a³, Figs. 4 and 10, of the corresponding common casing 45 wall A as well as through slots c¹⁹ of the key locking rockers c¹⁸. The two pin extensions c¹⁷, c²² overlap each other by flattened portions, Figs. 10 and 11, in such a manner that upon the feeler c³ of the differential member C⁰ being stopped the feeler c³ of the differential member C¹ is likewise stopped, while the feeler of the differential member C⁰ is allowed to move independently 50 of the differential member C¹ in the direction of its differential motion. Therefore, if none of the keys A, C, R but only one of the keys I to V is depressed, the differential member C¹ will move unhinderedly past the keys A, C, R and continue its movement 55 until the differential member C⁰ is disengaged from the engaging disk c¹⁰ and locked by its feeler striking against the depressed special key (I to V). When this takes place 60 the stop pin c¹⁷ stops the feeler of the differential member C¹ by means of the stop pin

c²³ so that the member C¹ is likewise uncoupled and locked and both differential members C¹ and C⁰ are brought into the same position, which corresponds to the depressed key of the row of keys I to V.

70

As will be described hereinafter, the positioning of the differential member C¹ causes one of eight auxiliary totalizers to be brought into cooperative engagement, five of these totalizers being designed to register the cash sales of the several sellers (sellers' totalizers I to V). The selection of one of these sellers' totalizers by means of the differential member C¹ is controlled by depressing one of the keys I to V. In this case it is necessary that none of the keys A, C, R is depressed. The differential member C¹ is in this case arrested by the feeler c³ of the differential member C⁰ through the intermediary of the pin extensions c¹⁷, c²³. The three other totalizers serve to register in common special transactions of all sellers (expenses, credit, bills). In such cases there is depressed besides the seller's key (I to V) the respective special key (A, C, R) and the selecting of the special totalizer is effected by positioning the differential member C¹, the appropriate feeler c³ striking against the depressed special key (A, C, R).

The described arrangement has for its object to cause the differential member C¹ which is connected alone with the selecting device for the sellers' totalizing I to V and transaction totalizers A, C, R, to be positioned always so as to actuate one of these totalizers no matter which keys may have been depressed. As long as cash sales are registered, with which none of the keys A, C, R is depressed, the amounts are accumulated in the individual totalizers allotted to the individual sellers (I to V). In case, however, one of the transactions A, C, R is recorded by a seller, the amount in consideration is not transmitted to the respective seller's totalizer but to the totalizer corresponding to that transaction.

Arranged to mesh with a toothed portion b⁹, Fig. 2, of each differential member B¹ is a pinion b¹¹, Fig. 1, rotatable on a shaft b¹⁰ and adapted to be coupled by means of a swingingly arranged pinion b¹³ with a pinion b¹², Figs. 1 and 2, likewise mounted for rotation on the shaft b¹⁰ and of the same size as pinion b¹¹. Each pinion b¹² is in mesh with a pinion f¹. The pinions f¹ are fastened to the ends of nested hollow shafts F which surround a shaft G mounted in the casing A¹ and extend into the drum G¹ rigidly connected to the shaft G. In the interior of the drum G¹ a toothed adding disk f² is fixed to the end of each hollow shaft F. The totalizers h¹ arranged in the frame H are adapted to be thrown into engagement with the adding disks f². The totalizer carriers H are mounted for rocking motion in

the head walls g^2 of the drum G^1 by means of pins h^2 , Fig. 3. Each frame H has mounted on it a roller h^3 . By the cooperation of the rollers h^3 with the arrangement herein-
5 after described, the frames H have imparted to them the rocking motion necessary for throwing the totalizers into or out of co-
operative engagement.

The toothed portion c^{14} of the differential member C^1 of the row of keys A, C, R meshes with an intermediate pinion i^1 , Fig. 1, mounted for rotation on the shaft b^{10} , Fig. 4, and meshing with a pinion i^2 . This pinion i^1 is fixed to one end of a hollow shaft i^3 sur-
10 rounding the outermost one of the nested hollow shafts F and the other end of which carries a slotted disk J. In a similar manner, a grooved cam disk K is in operative connection with the appropriate engaging
15 disk c^{10} through an intermediate pinion k^1 rotatable on the shaft b^{10} and in mesh with a toothed portion c^{15} of the disk c^{10} , through a pinion k^2 cooperating with the pinion k^1 and through a hollow shaft k^3 surrounding
20 the hollow shaft i^3 . The disk J carries in its slot a block J^4 slideable in radial direction, see particularly Figs. 7 and 8. The block J^4 is provided with an arc-shaped groove i^5 traversing it. When the block J^4 is in its
25 outermost radial position, Fig. 7, an annular groove i^6 concentrical to the axis of the hollow shaft i^3 and extending up to the two sides of the block J^4 , is completed by the groove i^5 into a closed ring which traverses
30 the block J^4 . This annular groove is engaged by the adjusting pins (rollers h^3) of the totalizer carriers H so that by rotating the disk J the block J^4 is either adjusted to register with the roller h^3 of one of the
35 totalizer carriers or with the idle place, Fig.
40 7. The shifting of the block J^4 takes place by means of the section k^5 of a curved groove k^4 , k^5 provided on the disk K and engaged by a roller i^7 carried by the block J^4 . The
45 section k^4 of the groove k^4 , k^5 lies concentri-
50 cally with relation to the axis of the hollow shaft k^3 . As long as the roller i^7 of the block J^4 is in engagement with the groove section k^4 , the block J^4 remains in its inner-
most position. During this time the total-
izer which has its adjusting roller h^3 in en-
gagement with the groove i^6 of the block,
is coupled with the adding disks f^2 . If
55 during the rotation of the disk K the roller
 i^7 enters the section k^5 of the groove k^4 , k^5 , the block J^4 is shifted radially and the totalizer carrier H rocked about the axis of the pins h^2 .

The operation of the described arrange-
60 ment is as follows:

By depressing amount keys B the adjust-
ment of the respective adding disks f^2 and
by depressing one of the special keys C the
adjustment of the appropriate totalizer h^1 is

prepared. When the machine is operated 65 the amount differential members B^1 are first restored by the engaging disks b^5 from the position they assumed from the previous op-
eration into zero position. During this stage
70 the coupling pinions b^{13} are rocked out of action so that the adding disks f^2 are not in connection with the differential members B^1 . The differential members B^1 are then carried upwards by the engaging disks b^5 until stopped by the depressed keys. The adding 75 movement thus limited of the differential members B^1 is transmitted to the adding disks f^2 which are positively connected with the members B^1 after the coupling pinions b^{13} have been thrown in, and to the totalizer 80 h^1 which is in engagement with the adding disks f^2 .

If none of the special keys I to V and A, C, R for one of the totalizers is depressed, 85 the two differential members C^1 and C^0 , how-
ever, are moved by the engaging disks c^{10} up to the uppermost position which in the machine shown is the tenth place, Fig. 4. For the rest, the mode of operation of the engaging disks c^{10} and of the differential members C^1 and C^0 is the same as that of the engaging disks b^5 and differential mem-
bers B^1 of the amount differential mech-
anism. However, owing to the driving ac-
tion of the grooved disks E², the positioning 90 takes place so much quicker that the full os-
cillatory movement of the engaging disks c^{10} (upward and downward) is already termi-
nated when the disks b^5 and the differential
members B^1 have reached the zero-position 95 (below). During the downward movement
of the engaging disk c^{10} the curved groove
 k^4 of the grooved disk K positively connected
to the disk c^{10} , causes the sliding block J^4
100 to be moved outwardly from the inner pos-
ition it assumed from the previous operation
of the machine; thus the roller h^3 of a total-
izer carrier H that happens to be in engage-
ment with the groove i^6 of block J^4 , is 105 moved back into the path of the annular
groove i^6 of the slotted disk J and the appro-
priate totalizer is placed out of engagement
with the adding disks f^2 . If the block J^4
110 was adjusted to the idle place, the said re-
versal of the block takes place during a ro-
tation of the disk K which corresponds to
the return movement of the differential
member C^1 and of the engaging disk c^{10}
115 from the tenth to the ninth place and if
the block J^4 was adjusted to one of the
rollers h^3 the reversal is accordingly effected
before the summit of the groove section k^5
120 coincides with the radial middle line of the
block J^4 . When all of the rollers h^3 of
the totalizer carriers H lie in the path of
the annular groove i^6 of the disk J, there
125 may take place the return rotation of the
disk J which is effected by the pin c^{13} im-

pinging on the differential member C^1 positively connected to the disk J . After the differential member C^1 and the engaging disk c^{10} have been restored into the lower-
 5 most position, Fig. 5, the disk c^{10} is again raised by the reversal of the crank drive, the coupling bolt c^2 of the differential member C^1 being carried along by the shoulder c^{12} of disk c^{10} up to the key stop and thereby
 10 disengaged from the engaging disk c^{10} and locked. This adjustment of the differential member C^1 and of the slotted disk J positively connected with the member C^1 causes the sliding block J^4 to be adjusted to the
 15 totalizer carrier H corresponding to the depressed special key, whereupon the cam groove disk K the rotation of which is continued up to the tenth place, shifts the sliding block J^4 inwardly through the inter-
 20 intermediary of the curved groove section k^5 and of the roller i^7 and causes the selected totalizer h^1 to be thrown into engagement with the teeth of the adding disks f^2 . Now, by coupling the pinions b^{11} , b^{12} positive con-
 25 nection is then established between the amount differential members B^1 which have in the meantime been moved down, and the appropriate adding disks f^2 , whereupon these differential members are positioned by
 30 the upward movement of the engaging disks b^5 . The adding movements imparted to the differential members B^1 are thereby transmitted by the adding disks f^2 to the totalizer h^1 which has been moved into cooperative engagement. Upon the adding movement having been terminated the pinions
 35 b^{11} , b^{12} are uncoupled.

Claims:

1. In a machine of the class described a
 40 row of keys, a differentially actuating member differentially stopped by one of said keys, another row of keys and another differentially actuating member differentially stopped by one of the last named keys and
 45 connections between said differentially actuating members whereby the one member is stopped through the medium of the other

one, when the latter is stopped by one of its keys.

2. In a cash register comprising a plurality of rows of keys and of differentially movable members influenced by the keys, two differentially movable members of two key-rows being provided with stop pins arranged for cooperation with each other in such a manner that a depressed key of one of the two key-rows through the intermediary of said stop pins stops the movement of the differentially movable member of the other key-row if no key is depressed in the latter.

3. In a cash register comprising a plurality of rows of keys and of differentially movable members influenced by the keys, two differentially movable members of two key-rows being provided with cooperating stop pins, and the keys of the one row being arranged in the direction of differential movement in such a manner with relation to the keys of the other row that, in the setting operation, the differential movable member of the first-said key-row will only come into the range of its keys upon the differentially movable member of the other key-row having moved beyond the range of its keys.

4. In a cash register comprising a plurality of rows of keys, differentially movable members influenced by the keys and operating members for the differentially movable members, two differentially movable members of two key-rows being provided with stop pins arranged for cooperation with each other, the stop pin of one of the two differentially movable members being arranged at the feeler of a bolt coupling including a coupling bolt so that this bolt is disengaged from its operating member and locked to the key-bank either by the said feeler striking against the depressed key or against the stop pin of the other differentially movable member.

The foregoing specification signed at Cologne Germany, this 14th day of April, 1925.

ERNST BREITLING.
